United States Patent Office

Des. 189,102
Patented Oct. 25, 1960

189,102

CAN OPENER

Alexander M. Grant, 906 Bay Oaks, Houston, Tex.

Filed July 21, 1959, Ser. No. 56,873

Term of patent 14 years

(Cl. D44—29)

Fig. 1 is an isometric view of a can opener showing my new design wherein the handle portion is curved; and

Fig. 2 is an isometric view of another embodiment of my new design wherein the handle portion is angled.

I claim:

The ornamental design for a can opener, as shown and described.
